(57) CLAIM

The ornamental design for a packaged transaction card product, as shown and described.

DESCRIPTION

FIG. 1 is a top and front perspective view of a packaged transaction card product showing our new design;

FIG. 2 is a front view thereof;

FIG. 3 is a rear view thereof;

FIG. 4 is a right side view thereof, the left side view being
a mirror image of the right side view;

FIG. 5 is a top view thereof; and

FIG. 6 is a bottom view thereof.

FIG. 7 is a top and front perspective view of a packaged transaction card product of FIG. 1 shown in an example of use with additional, unclaimed products, in the form of an envelope and a greeting card, within a bag portion of the packaged transaction card product;

FIG. 8 is a front view thereof;

FIG. 9 is a rear view thereof;

FIG. 10 is a right side view thereof, the left side view being
a mirror image of the right side view;

FIG. 11 is a top view thereof; and,

FIG. 12 is a bottom view thereof.

In the drawings, the broken lines depict unclaimed subject matter only and form no part of the claimed design. The features shown in long dash-short dash bolded broken lines indicate the bounds of the claimed design and otherwise form no part of the claimed design.
